UNITED STATES PATENT OFFICE

ALBERT D. JUDD, OF WALLINGFORD, CONNECTICUT, ASSIGNOR TO
MATTHEW DEAN & CO., OF NEW YORK, N. Y.

DESIGN FOR A NUT-CRACKER.

SPECIFICATION forming part of Design No. 17,446, dated July 12, 1887.

Application filed June 20, 1887. Serial No. 211,931. Term of patent 7 years.

To all whom it may concern:

Be it known that I, ALBERT D. JUDD, of Wallingford, in the county of New Haven and State of Connecticut, have invented a new 5 Design for Nut Crackers; and I do hereby declare the following, when taken in connection with accompanying drawing and the letters of reference marked thereon, to be a full, clear, and exact description of the same, and which 10 said drawing constitutes part of this specification, and represents a face view of one handle.

This invention relates to a design for the levers of that class of nut crackers which are 15 composed of a pair of levers hinged together at one end by a link; and the design consists in the shape and ornamentation of the handle, as shown in the accompanying illustration and hereinafter described.

20 The handles are of equal width from the hinge end to the tip, except for a portion midway of their length, where they are reduced in width. The tips terminate in a semicircle. On the surface from the hinge for little more 25 than one-third of the length of the handle is

represented a panel, the surface of which within the border represents series of diagonal ribs. From the tip about the same distance the surface represents a panel, its surface ornamented with a series of Gothic-shaped figures. Midway of the handle, and between the two panels, the surface represents a series of transverse ribs with a central longitudinal rib extending from one panel to the other, as shown in the accompanying illustration. 30 35

I claim—

The design for a nut-cracker, consisting in the lever representing a panel at the hinge end, the surface of which presents series of diagonal ribs, with a panel at the tip end, the surface 40 of which represents a series of Gothic figures, the surface of the handle between the two panels representing a series of transverse ribs, as described, and shown in the accompanying illustration.

ALBERT D. JUDD.
